UNITED STATES PATENT OFFICE.

CHARLES B. PUSHEE, OF MASON CITY, IOWA.

FOOT-SCRAPER.

SPECIFICATION forming part of Letters Patent No. 286,329, dated October 9, 1883.

Application filed May 16, 1883. (No model.)

To all whom it may concern:

Be it known that I, CHARLES B. PUSHEE, a citizen of the United States, residing at Mason City, in the county of Cerro Gordo and State of Iowa, have invented a new and useful Foot-Scraper, of which the following is a specification, reference being had to the accompanying drawings.

This invention relates to foot-scrappers; and it consists in certain improvements in the construction of the same which have for their object to produce a device which shall be simple, convenient, and inexpensive, and in which the brushes may be easily renewed when worn out, as will be hereinafter fully described, and particularly pointed out in the claims.

In the drawings hereto annexed, Figure 1 is a perspective view of my improved foot-scraper, the brush having been removed. Fig. 2 is a horizontal sectional view. Fig. 3 is a perspective view of the device complete, and Fig. 4 is a transverse sectional view.

The same letters refer to the same parts in all the figures.

25 A in the drawings designates the frame or body of my improved foot-scraper, which consists, mainly, of a strip or piece of metal, preferably wrought-iron, which is mounted in a vertical position on suitable feet, B B, the lower ends of which have perforations C C, to receive the screws or nails by which the device is fastened to the floor in position for operation. The body-piece A is bent so as to form a loop or recess, D, extending for about one-half its length from one end toward the middle. In the piece A, at the outer end of the recess D, is formed a vertical slot, E, and at the inner end of said recess a horizontal slot, F, is formed.

40 G is a clasp, formed of strong spring-metal, and having at one end a catch, H, adapted to engage the vertical slot E in the piece A. The other end of the said clasp is twisted to a horizontal position, so as to pass through the horizontal slot F at the inner end of recess D, and it is provided with a slot, I, to receive a wedge-shaped key or fastener, J. The clasp G is bent so as to form a recess, K, in the side adjoining the recess D of the body-piece A.

L is a brush, which may be made of broom-corn, of rolled textile fabric—such as old carpeting—or of any other suitable material. This is inserted between the body A and clasp G in the recesses D K, and it is clamped and held securely in position by driving the wedge 55 J in the slot I of the clasp. The brush is made of such length that its lower end shall rest upon the floor, thereby preventing the said brush from slipping out of its proper position. The upper edges of the recesses D and K of the body A and clasp G are also provided with inturned flanges M, which will enter the sides of the brush and hold the latter with absolute security.

The operation of my invention will be readily understood. The upper edge of the body A, adjoining the recess D, forms a scraper for cleaning the soles of the feet, which may afterward be wiped upon the brush. The brush, when worn out, may be readily replaced by cutting down an old broom and securing it by the clasp.

I claim as my invention and desire to secure by Letters Patent of the United States—

1. The combination, with the body-piece A, 75 having the recess D and slots E and F, of the clasp G, having catch H at the end thereof, and having its other end bent to a horizontal position, and provided with a slot, I, and the wedge J, substantially as and for the purpose set forth.

2. The combination of the body A, mounted on suitable feet, and having recess D, slots E F, and inturned flange M at the upper edge of the recess D, the clasp G, having recess K, 85 provided with inturned flange M at its upper edge, catch H, and a twisted end provided with a slot, I, the wedge J, and a brush held between the body A and clasp G, and having its lower end resting upon the floor, substantially as and for the purpose set forth.

In testimony that I claim the foregoing as my own I have hereto affixed my signature in presence of two witnesses.

CHARLES B. PUSHEE.
